UNITED STATES PATENT OFFICE.

JOHN I. HOKE, OF SOUTH BEND, INDIANA.

SULKY-PLOW.

SPECIFICATION forming part of Letters Patent No. 286,540, dated October 9, 1883.

Application filed April 14, 1883. (No model.)

To all whom it may concern:

Be it known that I, JOHN I. HOKE, of South Bend, in the State of Indiana, have invented certain new and useful Improvements in Sulky-
5 Plows; and I do hereby declare that the following is a full, clear, and exact description thereof, reference being had to the accompanying drawings, and to the letters of reference marked thereon, which form part of this specification,
10 in which—

Figure 1 is a side view of my improved means for operating the draft-tongue. Fig. 2 is an enlarged bottom view of the forward part of Fig. 1, showing the jointed tongue and the
15 means for automatically locking and unlocking it by the draft of the team. Fig. 3 is a perspective view for the purpose of showing the bail or arched-axle support for the rear end of the plow, the lever for adjusting the
20 same, and the device by which the landside-wheel is adjusted. Fig. 4 is a perspective view
25 in detail, showing how the spring is applied to the bail or arched axle. Fig. 5 is a perspective view, showing how the spring support for the draft-tongue is held and adjusted.

Fig. 6 is a perspective view of the device for adjusting the clevis which supports the draw-bar B. Fig. 7 shows the clip which holds the pin about which the plow swings and by means
30 of which the plow is flexibly attached to the sulky-frame. Fig. 8 is a diagram showing the different positions of lever X and its slot-
35 ted stub-axle slide in adjusting the landside-wheel.

35 This invention relates to novel improvements on arched-axle sulky-plows; and it consists in certain novel devices, which will be fully understood from the following description, when taken in connection with the annexed drawings.

40 I will here state that many of the devices and combinations of devices which I shall herein describe and claim are improvements on Letters Patent which have been previously granted to me. The arched or bail axle d' is round in cross-section, and to its left or landside end is bolted a vertical guide, V, to which is applied the slide U, bearing the stub-axle f', which slide, with its axle f'', is adjusted by

means of an angular lever, X, turning about a pin, X', and throwing its wrist-pin X'' forward and backward in a slot, W, formed in the head of the slide U, as indicated in Fig. 8. The slot W extends farther to the right of the vertical center of slide U than to its left, and the angular lever X is pivoted to the left of the vertical center of guide V. This arrangement of the parts causes the lever X to lift more vertically over the center of the load, and enables this lever to lift through a space equal to twice the length of the short arm thereof, as indicated in Fig. 8. Lever X is held in position by a toothed segment and latch, in the usual manner.

50 In this machine the plow is swung directly on the bail Z by a broad loop, a', while the bail itself is connected to lever Y by a leaf-spring, T. (Shown in Figs. 3 and 4.) The lever Y turns loosely on the crank end of the said bail. The spring T is rigidly attached to the bail and loosely to the lever by a loop, t'. The lever thus presses against spring T at t', which turns bail Z through its rigid connection therewith.

55 It is obvious that the support for the plow is a spring-support, enabling the plow to run undisturbed by the vertical motions of the sulky, caused by the wheels passing over uneven ground. Lever Y is secured by a toothed segment and latch to frame C', in the usual manner. The furrow side or arm of the axle d' is bent slightly forward to carry its wheel on axle-arm f' clear of the earth as the plow turns it. The U-shaped part C' of the sulky-frame and the axle d' are connected by a wooden frame, K, to the front end of which latter is bolted the jointed tongue, at D, and the plow-beam by the king-bolt or pin P. The draft-tongue articulates vertically on bolt D, and its motion in this direction is limited by the flexibility of a leaf-spring, J, the free end of which is held by an adjustable loop, L, secured to the frame or beam K, as shown in Figs. 1, 3, and 5.

60 Beneath loop L (see Fig. 3) is shown a foot-rest for the driver when on his seat, and by the side of this foot-rest I show an extension, M, of the tongue F, which serves as a foot-

piece by which to depress the rear end of the tongue, and thus raise its front end. This has the effect of depressing the point of the plow, so that it will keep its depth in passing through hard spots in the field. These being passed, by simply removing the foot from extension M the spring J will return the parts back to their normal positions. By means of loop L the pitch or dip of the plow 10 can be regulated and the plow set for any kind of soil.

The jointed tongue G is hinged at H, and to its bottom side is fixed the double or heart-shaped cam E. (Shown clearly in Fig. 2.) A latch, D⁴, plays back and forth on the under side of section F of said tongue. Through staples, and near the nose of the latch D⁴, the end of a connecting-rod, c', passes through a hole in an offset shoulder, K'. The rod c' has a 20 collar, c², on it, by which it pushes latch D⁴ into the notch of cam E when locking the tongue. The said connecting-rod c' extends backward and downward, and then, by a square turn, its rear end passes under the front end of the plow-beam, and terminates in an eye, c³, through which draw-bar B slides freely. The extent of play given to the latch D⁴ is determined by the position of a nut, o, which is adjustable forward or backward on the draw-bar B. The front 25 end of the draw-bar passes freely through a hole in the clevis S. By means of a slot through this clevis (see Fig. 6) it can be adjusted up or down to regulate the direction of the draft. This clevis is bolted to the clip N, that is 30 rigidly fixed to the front end of the plow-beam.

For clearness of description, the clip N may be called the "fixed part" of the clevis, and S the "adjustable piece" through which the 40 draft-rod passes. As the team starts, the draft-rod B, by means of nut o and rod c', throws the latch against the inclined side of heart-cam E, and, as the team pulls, the tongue will be straightened and locked. When the team 45 stops pulling, the tongue is free to move either to the right or left, and the plow is drawn around as in my patent above referred to.

It will be seen that by means of the adjustable finger b², which is provided with a set-screw, b³, and through which the long loop a' passes, the plow can be held rigidly at one place on the bail Z; or by loosening the set-screw b² it can be allowed to swing free.

It is obvious from the above description 55 that I have not only added to, but that I have taken from, the machine heretofore patented to me devices for the purpose of more fully and practically carrying out and perfecting my machine; and it will now be seen 60 that I have a machine which is better arranged for the purpose of turning a sod with a sulky-plow.

Having thus fully described my invention, what I claim as new, and desire to secure by 65 Letters Patent, is—

1. The combination of the plow, the suspension-loop, and the adjustable connecting-loop, with the vertically-adjustable bail, a hand-lever, and a leaf-spring, all constructed and adapted to operate substantially in the manner and for the purposes described. 70

2. The combination, in a sulky-plow, of the long loop a', fixed to the plow-beam, the adjustable loop, through which loop a' passes freely, a plow-beam, a vertically-adjustable bail, and a lever fixed to one of the cranked arms of this bail, and a spring, T, all constructed and adapted to operate substantially in the manner and for the purposes described. 75

3. For the purpose of actuating the bail Z from which the rear portion of the plow is suspended the hand-lever Y, the spring T, and its loop t', applied to the said bail, substantially as described. 80

4. The combination of the extensions of the U-shaped frame back of the arched axle, the vertically-movable bail, the plow suspended from this bail, and laterally adjustable by means of a long loop and slide, a leaf-spring, and a hand-lever connected thereto loosely, all constructed and adapted to operate substantially in the manner and for the purposes described. 85

5. The combination of the bail Z, the frame C', the hand-lever Y, the spring fast on the furrow end of the said bail, and the loop t', and the notched segment and catch, all constructed and adapted to operate substantially in the manner and for the purposes described. 90

6. The combination of the jointed tongue, the plow-beam, a draft-tongue, articulating vertically, a spring, J, an adjustable loop for this spring, and the beam K, all arranged and adapted to operate substantially in the manner and for the purposes described. 95

7. The combination of the spring J, the extension M, the tongue F, and the loop L, all constructed and adapted to operate substantially in the manner and for the purposes described. 100

8. The combination of the jointed tongue, hinged at H, the heart-shaped cam, the latch, the actuating parts of this latch, and the section F, all constructed and adapted to operate substantially in the manner, and for the purposes described. 105

9. The combination, with the heart-shaped cam, its latch, the connecting-rod, the draw-bar, and the clevis, all constructed and adapted to operate substantially in the manner and for the purposes described. 110

10. The combination of the double or heart-shaped cam, the connecting-rod passed through a hole in an offset shoulder, K', the collar c², and the adjusting-nut on said connecting-rod, all constructed and adapted to operate substantially in the manner and for the purposes described. 115

11. The combination, in a sulky-plow, of
a sectional pivoted tongue, having a joint
which admits of lateral movement, a joint
which admits of vertical movement, an auto-
matic engaging and disengaging device, and
a spring which passes through an adjustable
loop, all constructed and adapted to operate
substantially in the manner and for the pur-
poses described.

In testimony that I claim the foregoing as to
my own I affix my signature in presence of
two witnesses.

JOHN I. HOKE.
